INCANDESCENT FILAMENT SUPPORT
AND METHODLorin W. Curtis, Verona, N. J., assignor to Tung-
Sol Electric, Inc., a corporation of Delaware

Application October 10, 1950, Serial No. 189,391

6 Claims. (Cl. 313—37)

1

This invention relates to incandescent lamps and more particularly to supporting means for the filament in the form of support wires that provide mechanical support for the filament as well as the means for the supply of electric power.

Ordinarily the legs of an incandescent filament are welded to the ends of the support wires by a resistance welding or embedding process. In this process the filament legs are welded to the weld pad which is a flattened portion on the end of the support wire, and it is preferable of course to embed the filament leg in this pad.

This type of supporting means for the filament has not been found to be entirely satisfactory, especially in high wattage, low voltage type miniature lamps such as those used for automotive lighting. It has been found that the filament legs may fracture at a point immediately adjacent the weld points long before the filament itself would actually burn out. It has also been found that due to the frequent heating and cooling periods encountered in night driving, the physical characteristics of the metal support wires become greatly changed and cause the filament leg to become loose and eventually fall out of actual contact with the support wire.

The heat generated by the filament that must be dissipated at the juncture of the filament leg and the support wire comes from three sources, (a) conduction through the legs of the filament, (b) convection through the gas atmosphere surrounding the filament, and (c) the heat generated because of the resistance of the weld and the high currents encountered particularly in low voltage automotive lighting. The greatest source of heat is of course that which is conducted to the weld through the filament legs.

The filament support means in accordance with this invention operates to by-pass that heat that would normally arrive at the weld through the filament legs around the weld and into the support wire. Actual tests have indicated that with this procedure much of the weld depreciation vanishes and the life of the lamp is greatly increased.

The above and other objects of this invention will become more apparent from the following description and accompanying drawings forming a part of this application.

In the drawings —

Fig. 1 is a side elevation of an incandescent lamp in accordance with the invention;

Fig. 2 is an enlarged view of the filament and supporting wires of the incandescent lamp shown in Fig. 1 to show mechanical and electrical con-

2

nections between the filament legs and the support wires;

Fig. 3 is a perspective view of one form of the invention;

5 Fig. 4 is a cross-sectional view taken along the line 4—4 of Fig. 3;

Fig. 5 is a perspective view of another form of the invention;

10 Fig. 6 is a cross-sectional view taken along the line 6—6 of Fig. 6;

Fig. 7 is a perspective view of still another form of the invention; and

Fig. 8 is a cross-sectional view taken along the line 8—8 of Fig. 7.

15 Although the invention will be described particularly in connection with automotive head lamps of the high wattage, low voltage type, it will be apparent that it is useful in other incandescent lamp applications wherein difficulties are 20 encountered in connecting the filament legs with the support wires.

With reference to Figs. 1 to 4, 1 denotes an incandescent lamp having a glass envelope 2, a base 3, and electrical connectors 4 extending 25 from the bottom of the base. Within the glass envelope 2 are a pair of filament support wires 5 and 6 extending upwardly from the glass press 7. These wires 5 and 6 also pass downwardly 30 into the base 3 and are connected to two of the terminals 4. In double filament lamps all three of the terminals 4 would be used with one terminal being common to the two filaments. The filament 8 within the glass envelope 2 is formed 35 with a pair of legs 9 and 10 welded, respectively, to the support wires 5 and 6. The weld points are denoted by the numerals 11 and 12 and are spaced from the inner ends of the support wires 5 and 6.

The inner ends of the support wires 5 and 6 40 are flattened as shown at 13 and 14 and are formed so that the legs 9 and 10 bear against these flattened portions when they are welded at points 11 and 12 to the support wires 5 and 6. That part of each filament leg between the flats 45 13, 14 and the welds 11, 12 is spaced from its support wire so that the gas within the lamp can circulate thereabout.

The invention can perhaps be more clearly seen in Figs. 3 and 4 of the drawings. Like numerals 50 have been used to designate corresponding components in all figures. The support wire 5 is formed with the flattened portion 13 at the very end of the wire and with a second flat 15 spaced from the first flattened portion 13 and 55 connected by a depressed flattened part 16. The

flat 15 is preferably made slightly higher than the flat 13 so that the filament leg 9 can be substantially wholly embedded in the flat 15 during the formation of the weld 11 so that that part of the filament leg 9 overlying the flat 13 will bear snugly against the flat 13 without any deformation of the filament leg part 9' between the flats 13 and 15.

With this structure it has been found that the major source of heat that normally causes failure of the weld, that is the heat arriving at the weld by conduction through the filament leg 9, is by-passed by reason of the contact of the filament leg 9 with the flat 13. A substantial part of the heat leaves the filament leg upon its contact with the flat 13 and is then conducted around the weld and into the support wire body 5.

This procedure has been found most effective in securing long lasting welds and extending the life of the lamp in most instances to that of the filament.

It is important to note that the filament leg 9 is not welded or otherwise securely fastened to the flattened part 13 of the support wire but is free to move relative to the flat to eliminate stresses or strains that would be produced by reason of different coefficients of expansion of the filament leg material that is usually tungsten and the support wire material normally made of nickel.

In Figs. 5 and 6, which illustrate a modification of the form of the invention shown in Fig. 3, the flat 13 on the end of the support wire 5 is shaped in the form of a V, denoted by the numeral 17, to limit the sidewise motion of the filament and yet permit the leg 9 to expand and contract with changes in temperature without setting up stresses or strains that may destroy the weld.

Figs. 7 and 8 illustrate still another form of the invention wherein the end of the support wire, instead of being flattened as shown at 13, Fig. 3, is merely provided with a groove 18 through which the filament leg 9 passes.

I claim:

1. A mount for an incandescent lamp filament comprising; a welding surface formed on said mount at a point spaced from one end thereof

for welding a filament thereto; and a contacting surface formed at said end of the mount mechanically contacting the leg of said filament, the part of the mount between the mechanical 5 contacting and welding surfaces being depressed below said surfaces.

2. In an incandescent lamp, a mount for attachment of a filament leg thereto comprising: means spaced from the end of the mount for 10 welding attachment of the filament leg; and means between the weld and said end of the mount contacting the filament leg to conduct heat therefrom.

3. The mount according to claim 2 wherein 15 said means for contacting the filament leg comprises a flattened part adjacent said end of the mount and bearing against the filament leg.

4. The mount according to claim 2 wherein 20 said contacting means comprises a V-shaped groove formed in said mount adjacent said end thereof for reception of the filament leg therein.

5. The mount according to claim 2 wherein 25 said contacting means comprises a slot formed in said mount for reception of the filament leg therein.

6. The method of attaching the leg of an incandescent filament to a mount, comprising welding the filament to the mount at a point spaced from one end thereof and bringing the filament 30 leg into heat conductive engagement with the mount at a point between the weld and the filament with at least part of the leg between the weld and the point of heat conductive engagement spaced from the support wire.
